UNITED STATES PATENT OFFICE.

FRANK KUHN, OF DETROIT, MICHIGAN, ASSIGNOR TO AMERICAN ELECTRICAL HEATER COMPANY, OF DETROIT, MICHIGAN, A CORPORATION OF MICHIGAN.

ELECTRICALLY-HEATED SAD-IRON.

1,096,926.

Specification of Letters Patent. Patented May 19, 1914.

Application filed February 25, 1911. Serial No. 610,913.

To all whom it may concern:

Be it known that I, FRANK KUHN, a citizen of the United States of America, residing at Detroit, in the county of Wayne and State of Michigan, have invented certain new and useful Improvements in Electrically-Heated Sad-Irons, of which the following is a specification, reference being had therein to the accompanying drawings.

0 The invention relates to electrically heated sad-irons and consists in various features of construction as hereinafter set forth.

In the drawings,—Figure 1 is a vertical central longitudinal section; Fig. 2 is a perspective view of the guide and holder for the attachment plug; and Fig. 3 is a perspective view of the heat distributing plate; Fig. 4 is a perspective view of the heating element; Fig. 5 is a perspective view of the bottom section.

My improvements are applicable to sad-irons of that type in which the heating element is removably secured to the body of the iron. The object of such construction is to permit replacement of the unit when necessary, and it is desirable that this operation should require as little mechanical skill as possible so that it may be performed by the ordinary user of the iron. I have therefore, devised a construction of unit provided with a metal case or sheathing which will protect the resistance element from injury without interference with the rapid dissipation of heat therefrom. This heating unit is fashioned to extend over the body of the iron parallel to the work face and is clamped thereto by a superposed heat distributing member, the result being that the heat is uniformly distributed through both the body and the distributing member.

The particular feature of the invention is the peculiar arrangement and combination of the unit, the work body and the superposed heat distributing member. These are so proportioned that the heating element is a flat thin structure arranged between plates of considerably greater thickness, respectively forming the work body and heat distributing member. Furthermore, the work body and heat distributing member

are substantially the same in thickness and in mass, while their interior faces are machined to accurately contact with the sheathing of the heating element. Such an arrangement has several advantages. First, 55 the equal thickness and substantially equal mass of the bodies above and below the element will prevent the warping of the iron which frequently occurs where the element is clamped between plates of unequal thickness; second, the heat generated in the resistance element will pass rapidly through the thin walls of the sheathing and is distributed with uniformity over the entire work surface of the iron.

Another feature of the invention is the construction of the hood and handle combined therewith, and further, the means employed for guiding and supporting the terminal plug.

In detail A is the bottom section or body of the iron preferably formed of case metal and having parallel bottom and top faces, B is the heating element arranged above the plate A and of substantially the same area 75 as the upper face thereof. The internal construction of this heating element forms no part of the present invention but the arrangement is such that the resistance is inclosed in a thin flat metallic sheathing having insulated terminals C, C' mechanically secured to and extending outward therefrom. The element is also preferably cut away in the center to prevent overheating at this point, and also to provide space for the 80 passage of the clamping screws.

D is the heat distributing plate which is of the same form as the members A and B and is arranged thereabove, being the same in thickness as the plate A.

E, E' are the clamping screws passing through the plate D and the central aperture F in the element B and engaging threaded apertures in the plate A. One of these screws E' has an upward extension E' 95 which is used for securing in position the hood G. This hood is preferably formed of a single sheet metal blank bent into the desired shape, the lower edge resting upon point bearings H around the margin of the 100

member A, the amount of contacting surface being very limited so as to reduce to the minimum the heat conduction. The handle I is secured to the hood preferably by a 5 pair of bent bars J which at their lower ends pass through apertures in the hood and are bent to form hook portions J' which are electrically welded, riveted or otherwise secured to the hood. Thus the hood and the 10 handle constitute a very light structure and all the necessary weight of the iron may be concentrated in the members A and D.

The terminals C, C' extend upward from the member D and are provided with terminal contact posts K and K' which pass outward through apertures in the hood in rear of the handle, while insulator bushings L and L' prevent contact of the posts with the hood. The terminal posts K, K' are 15 parallel to each other and are adapted to receive the insulated plug member which is at the end of the flexible conductor, the arrangement being similar to that heretofore employed in irons of this type. With these 20 previous constructions however, the plug is supported solely by its engagement with the terminal posts and the strain sometimes exerted on the conductor has a tendency to bend the posts or to break the plug which 25 is usually formed of fragile material. I therefore provide a socket member for receiving the plug and mechanically supporting it independently of its connection with the terminal posts. As shown this member 30 M is formed of sheet metal and is fashioned to have a shank portion N extending up to the handle I and secured thereto by the same bolt O which secures the handle to the bars J. From the point of attachment 35 40 the shank extends downward and rearward and is provided with a socket portion P in alinement with the posts K and K' and adapted to receive the outer end of the terminal plug. Thus in use, the plug will be 45 supported by this member and at the same time all direct heat conducting contact between the member M and the hood G is avoided.

In use, the heat generated in the unit B 50 passes directly through the body A to the work surface and also upward into the member D which forms a distributor and bal- 55 last. Inasmuch as these two members A and D are the same in thickness, substantially the same in mass and of the same material, the expansion and warping effected in the one is counteracted by the opposite tendency in the other, the result being that the warp- 60 ing of the body which would interfere with the trueness of the work surface is avoided. The hood G forms an effective heat guard and the member M guides and supports the terminal plug.

Whenever it is necessary to renew the ele- 65 ment all that is required is to disengage the

screws E and E', remove the hood and the member D and replace the element B, after which the parts may be re-assembled.

What I claim as my invention is:

1. In an electrically heated sad-iron, the 71 combination with the work body and heating element, of a hood formed of sheet metal, handle shanks extending through apertures in said hood and provided with hook portions within the hood, and a handle secured between said handle shanks. 71

2. In an electrically heated sad-iron, the 81 combination with the work body and heating element, of a hood formed of sheet metal, separate handle shanks passing through apertures in said hood and hooked beneath the same, means for securing said hook portions to the hood, and a handle secured between said shanks. 81

3. In an electrically heated instrument, 81 the combination with the work body, a heating element secured thereto, and terminals projecting outward from said heating element, of a hood apertured for the passage of said terminals therethrough, a handle for said hood, and a terminal plug support secured to said handle independent of said hood and in alinement with said terminals. 91

4. In an electrically heated sad-iron, the 91 combination with an apertured hood, electric terminal contacts projecting outward therethrough, a handle secured to said hood, and a plug support secured to said handle independent of said hood and in alinement with said terminals. 10

5. In an electrically heated sad-iron, the 10 combination with a hood, of a handle, a shank securing said handle to said hood, a terminal contact projecting outward from said hood, a plug support separated from said hood and in alinement with said terminal contact, and a shank for said plug support secured to said handle adjacent to said handle shank. 10

6. In an electrically heated sad-iron, the 11 combination with a work body and terminal contacts projecting outward therefrom, of a handle and a plug support in alinement with said terminal contacts and spaced from the work body, said plug support being secured to said handle. 11

7. An electrically heated sad iron, comprising a work body, a superposed heat distributing member, an electric heating unit clamped therebetween in substantially equal 12 heat conducting contact therewith, and a hood and handle removably connected to said work body, the greater portion of the weight of the iron being concentrated in said work body, heating unit, and heat distributing member. 12

8. In an electrically heated instrument, the combination of a work body, a superposed hood and in alinement with said outwardly- 13 secured to said hood, a detachable electric

heating unit clamped between said heat distributing member and work body and having terminals permanently secured thereto and passing outward through apertures in said hood, and a plug support secured to said handle in alinement with said terminals.

9. In an electrically heated sad iron, the combination with an apertured hood, of an electrical terminal contact projecting outward therethrough, a handle secured to said hood having a shank portion substantially

parallel to said outwardly-projecting contact, and means for supporting a terminal plug from said handle independent of said hood and in alinement with said outwardly-projecting contact.

In testimony whereof I affix my signature in presence of two witnesses.

FRANK KUHN.
